HAND WHEEL WRENCH

Wayne K. Bergman, Toledo, Ohio

Application February 28, 1956, Serial No. 40,396

Term of patent 14 years

(Cl. D54—16)

Figure 1 is a perspective view of a hand wheel wrench showing my new design;

Figure 2 is a side elevation view thereof;

Figure 3 is a top plan view; and

Figure 4 is a front elevation thereof.

I claim:

The ornamental design for a hand wheel wrench, as shown.
